UNITED STATES PATENT OFFICE.

CHARLES F. WILLIS, OF FERGUS FALLS, MINNESOTA, ASSIGNOR OF ONE-HALF TO ALVA H. KIRK, OF SAME PLACE.

AUTOMATIC TELEPHONE-CALL.

SPECIFICATION forming part of Letters Patent No. 350,610, dated October 12, 1886.

Application filed June 30, 1886. Serial No. 206,698. (Model.)

To all whom it may concern:

Be it known that I, CHARLES F. WILLIS, a citizen of the United States, residing at Fergus Falls, in the county of Otter Tail and State of Minnesota, have invented certain new and useful Improvements in Automatic Telephone-Calls, of which the following is a specification.

My invention relates to improvements in mechanisms for signaling-calls for the individual telephones of a series connected with a single line-wire; and the object of the invention is the production of devices which will enable the call for any one of such instruments to be made without sounding the call-bells of other instruments on the same line-wire.

The object is accomplished by means of the devices illustrated in the accompanying drawings, in which—

Figure 1 is an elevation of the devices in their case. Figs. 2 and 3 are respectively front and top views of a part of the mechanism, and Figs. 4 and 5 are detached views of portions of the same. Fig. 6 is an illustrative diagram showing a line-wire with three call-stations thereon and the circuits involved in the call-system; and Figs. 7 and 8 are detail views showing the armature and pawl-lever attached to the electro-magnet connected with an independent battery.

30 A represents a suitable case adapted to be secured to a wall for supporting the operative devices of my improvements, and A' the door of the case.

35 a are wires connected to the telephone-wire and extended into the case to the electro-magnets b, whose function is to actuate a lever to make and break the circuit of an independent battery which operates the devices of the improvement.

40 The independent battery 10 in Fig. 6 of the drawings may be located at any convenient place, and a wire, a', extends from it to a hollow electro-magnet, B, in the case. A wire, a'', connected to the magnet B, extends to a 45 copper plate or piece, c, secured to the case. Above the piece c is a copper plate, c', secured on a pivoted arm, e, and to this arm e is connected the wire a'', leading to the independent battery. A second arm, e', secured to turn 50 with the arm e on the pivot c'', extends in upright position, to be operated by an armature,

d, projecting below the magnets b, and provided with an insulating-plate, d', at its extremity. The arm e' bears against the plate d' when the armature d is in normal position, 55 and holds the copper pieces c c' from contact; but when the armature d is drawn to the magnets b the arm e' is permitted to move inward, and, carrying with it the arm e, brings together the two copper pieces c c', and completes 60 the circuit with the independent battery.

The electro-magnet B may be either solid-coved or hollow and produce the same results; but a hollow magnet is recommended, because it is believed to exert more power than a solid- 65 coved one of the same size.

B' is an armature hinged at the base of the magnet B and actuated by it. To this armature is attached, by riveting or otherwise, a vertical bar or lever, f, which is insulated from 70 the armature by vulcanized rubber or other suitable insulating material, b'. A spring, s, attached to the lever f, holds the armature B' away from its magnet when the circuit with the magnet is not complete, but when the circuit is made in the manner described the magnet overcomes the force of the spring s and draws the armature to it. The lever f carries a pivoted arm provided with a pawl, f', for 75 engaging notches g on the periphery of a segmental frame, G.

The segmental frame G is supported on a pivot, g', below the pawl, with the peripheral notches in position to be successively engaged by the pawl as the segment is turned on its 85 pivot by the pawl. At the side of the segment away from the pawl is an adjustable weight, g'', for turning the segment in that direction when free from the pawl. Below the line of the notches g is a button, k, pivoted to the 90 face of the segmental frame by an adjusting-screw, k'. The screw k' should clamp the button tight enough to the frame to hold it in place while allowing it to be turned by a light pressure at either extremity. The upper surface of the button k is below the lower line of the notches g, except an enlarged portion, k'', which projects above the bottom of the notch to which it is adjacent. In the frame G, under the several notches g are holes g'', tapped to 95 receive the screw k' when the location of the button is changed. The button is connected 100

to the face of the frame by passing its screw k' into such one of the holes g^2 as will place the part k^2 of the button in coincidence with the notch g of the series corresponding in number 5 with the call-number of the telephone with which the instrument is designed to be used. The pawl f' in entering the successive notches depresses the button k only when it enters the notch with which the enlargement k^2 is coincident. If the pawl reciprocations are continued after the button has been thus depressed, and the segmental frame is farther turned toward the right, the lower surface of the button is thereby made to pass over a stationary pin, 15 j , by which the button is again elevated to its original position, so that the signaling mechanism will not be made to operate when a greater number of calls has been made than the number at which the mechanism has been 20 set to operate.

i is a pawl, arranged to engage the notches g and hold the frame while the reciprocating pawl f' is making its advance movement. The mode of releasing the pawl i from engagement 25 will be hereinafter described.

m is a bar, pivoted at its middle, and has an inclined upper surface, m' , at its inner end. The outer end is held down by a spring, s . When the notches g have been released from 30 both pawls f' and i , the frame G is carried a partial turn backward by gravity, and the depressed end of the button k (if the button has been depressed by the pawl f' , and not afterward lifted by the pin j) bears upon the surface m' of the bar m and presses down that end of the bar. The button k , when not depressed, passes above the surface m' , and does not operate the bar m . The travel of the depressed end of the button over the inclined surface m' 35 is ordinarily sufficient to lift that end of the button to its normal position; but in case it is not elevated sufficiently by the surface m' , it will be made to rise to its proper position by sliding over a pin, l , held in the plane of the 40 surface m' by a fixed arm, l' .

It is obvious that the form and arrangement of the button k and of the parts in connection with which it performs its functions may be varied without departing from the principle 50 of operation; hence I do not wish to confine myself to the specific construction and arrangement shown.

The lowering of the inner end of the bar m raises its outer end to release a drop, n , which 55 then descends upon the post n' and closes the circuit to an electric bell, in the well-known manner.

n^2 is a lever for lifting the drop n , by means of its pin n^3 , to position to be engaged and held 60 by the bar m . A spring, s^2 , is provided for retracting the lever. The handle of the lever n^2 projects through a slot in the end of the case so that it can be operated from without the case. A button or hook, n^4 , is provided on 65 the outside of the case to hold the lever-handle down, when desired, to prevent the drop n from falling upon the post n' , and making the

circuit with the electric bell, and thus the ringing of the bell is prevented at times when it is desired that it should not ring.

o is a bar connected to the lever f and to a lever, p , which has a fulcrum, p' . Below the lower end of the lever p is a hollow rocking frame or tube, r , suspended on an arm, r' , on a pivot, r^2 . The arm r' has a slotted outward 75 portion, r^3 , in the slot r^4 of which the end of the lever p passes and rocks the frame as the lever is oscillated. Above the inner end of the frame r is a pivoted bar, t , the upper end of which is arranged to engage the end of a 80 rod, t' , attached to the lever of the pawl i , for turning the pawl to lift it out of engagement with the notches g . Within the frame r is a loose ball, v , which rolls from end to end of the frame as the frame is rocked by the movement of the lever p , and which when at the inner end of the frame bears against the side of the bar t and turns it on its pivot, thereby moving the rod t' to release the pawl i from the notches.

The operation of the mechanism is as follows: When a telephone-call of a given number is made on the line-wire, the electric current passing to the magnets B draws the armature d away from the arm e and allows contact to be made between the copper surfaces c c' . A circuit being thus established through the magnet B , the lever f is drawn over, moving with it the pawl f' and the arm o . The pawl rotates the segment G one notch for each ring of the bell or for each period of electric contact, while the frame r is tilted backward during each such period, causing the ball v to roll to the outer end of the frame. At the completion of the signaling and when the lever f falls away from the magnet B and its pawl f' is free from the notches g , the frame r is again tilted forward, and the ball v rolls down against the bar t and the pawl i is lifted out of engagement. The segmental frame G 110 is then free and falls back by gravity, and the button k , if the calls have been of the number for which it has been set to be operative, will, as it is carried along by the segment, depress the lever m and cause the electric bell to be 115 sounded in the manner described. If the calls have not been of the number for which the button was arranged to be operative, then the button will be in normal position, and as it is carried along by the segment will pass above 120 the bar m and the bell will not be sounded.

In Fig. 6 the call system is illustrated in diagram, showing a line-wire, 1, and ground-wire 2, with three stations on the line-wire, and call-operating apparatus connected therewith. The figure 3 represents the central office, and 4, 5, and 6 three telephones on the line-wire, and 7, 8, and 9 their respective call-instruments connected to the line-wire by the wires a a' . The call-instrument 7 for the telephone 4 may 125 be arranged, as it is shown in Figs. 1 and 2, to ring its electric bell when two calls are made from the central office, that, 8, for the telephone 5 for three calls, and that, 9, for the

telephone 6 for four calls. When calls are sent over the line from the central office, all of the call-instruments are set in operation, but, as will be readily understood from the foregoing description, the bell of that instrument only for which the call was intended will be sounded.

10 is the battery with which the wires a' a^3 are connected, and 11 is the battery with 10 which the wires w^2 are connected for ringing the bell 12.

My invention can be used for other purposes than telephone calls—as, for instance, for operating electric bells when the instrument is disconnected from a telephone. For this purpose the magnets b and the pivoted arms e e' and the parts connected therewith may be dispensed with, and the make and break of the circuit with the magnet B can be effected by a push-button in the door of the case, as illustrated in Fig. 1. One wire (shown by dotted line w) leading to the magnet B is connected to a spring-plate, x , operated by the button y and the other wire (shown by dotted lines w') is connected to a fixed plate, z , with which the spring-plate x is brought in contact by pressure of the button. The effect upon the operative mechanism, as is apparent, will be identical with that heretofore described for those parts when connected with a telephone.

I do not wish to be limited in the scope of my claims to the exact forms and arrangements of parts shown and described, but desire protection against such other forms and arrangements of parts as will produce substantially the same results by means that are equivalents of those shown and described.

What I claim, and desire to secure by Letters Patent, is—

40 1. In an electric-call apparatus, a movable frame provided with notches, a pawl actuated by an electro-magnet for engaging said notches to move the frame; a pivoted piece carried with said frame and arranged to be depressed by said pawl, and mechanism operated by said pivoted piece to ring a bell.

2. The combination, in an electric-call apparatus, of an electro-magnet, a pivoted frame, notches thereon, a pawl actuated by said electro-magnet for engaging said notches to turn the frame, a piece pivoted to said frame and provided with a projecting portion coincident with one of said notches, means for retracting said frame when released from said pawl, and mechanism for ringing a bell arranged to be set in operation by the return movement of said pivoted piece, substantially as described.

3. In combination, in an electric-call mechanism, an electro-magnet, a pivoted segmental frame, notches on the periphery thereof, a lever operated by said electro-magnet, a reciprocating pawl connected to said lever for engaging said notches, a stationary pivoted pawl for holding the frame, a button pivoted on the side of said frame and arranged to have one end depressed by the action of the reciprocating pawl in one only of said notches,

means for retracting said pivoted pawl from the notches and for releasing said frame, substantially as and for the purpose set forth.

4. The combination, for the purpose set forth, of a notched segmental frame, a button pivoted to said frame, a pawl for moving said frame and depressing said button, and means for elevating the depressed portion of said button by the forward movement of said frame after the button has been depressed, substantially as set forth.

5. In combination, in an electric-call apparatus, a pivoted frame, notches thereon, a lever actuated by an electro-magnet, a reciprocating pawl connected therewith for moving said frame, a stationary pivoted pawl for holding said frame a button pivoted at the side of said frame and arranged to be depressed by the action of the reciprocating pawl in one of said notches, means for releasing said pivoted pawl from the notches, and mechanism to be operated by the return movement of said button to ring an electric bell and to elevate said button to its normal position, substantially as set forth.

6. In combination, in an electric-call mechanism, a pivoted frame, notches thereon, a lever actuated by an electro-magnet, a reciprocating pawl operated thereby, a pivoted pawl for holding said frame, a button pivoted at the side of said frame and arranged to be depressed by the action of said pawl in one only of said notches, and a fixed surface for elevating the depressed portion of the button when moved beyond the point at which it was depressed, substantially as and for the purpose set forth.

7. In combination, in an electric-call apparatus, an electro-magnet, a lever actuated thereby, a reciprocating pawl connected to said lever, a segment-rack engaged thereby, a pivoted pawl for holding said rack when free from said reciprocating pawl, a pivoted hollow frame, a ball therein, a lever connected to the lever of said reciprocating pawl for rocking said frame, and a lever for releasing said pivoted pawl from the rack by the return movement of said ball, substantially as set forth.

8. In combination with a segment-rack and pawls for moving and holding the same, a hollow rocking frame, a rolling ball within said frame, levers for tilting said frame while the reciprocating pawl is moving said rack, and a lever operated by the return movement of said ball to disengage the holding-pawl when the reciprocating pawl has ceased to operate the rack, substantially as set forth.

9. In a telephone-call, electro-magnets connected to the telephone-wire, an independent electro-magnet and a battery therefor, means for completing the circuit in said independent magnet and battery by the operation of said first-named magnets, a segment-rack operated by said independent magnet, a button connected to said rack and arranged to ring an electric bell, substantially as set forth.

10. In an electric-call apparatus, a recipro-

eating pawl, a ratchet-wheel or rack operated therewith, a pivoted button carried with said wheel or rack, a projection on said button whereby an end of the button may be depressed by the entry of said pawl into one only of the notches of said wheel, a weight for retracting said wheel or rack, and mechanism arranged to be operated to ring a bell by the

pressure of the depressed portion of said button in performing its return movement and for simultaneously elevating said button to its normal position, substantially as set forth.

CHARLES F. WILLIS.
